PICTURE FRAME

Marshall E. Greenspon, Hartford, Conn.

Application February 19, 1946, Serial No. 648,733

3 Claims. (Cl. 40—155)

1

This invention relates to a picture frame and more particularly to a picture or photograph frame which is foldable and which is preferably constructed of sheet material.

An object of this invention is to provide a frame which will support a picture in an upright position and provide a recessed frame around the picture.

A further object of the invention is to provide such a frame which may be readily folded into a flat position, when not in use, so that it may be easily carried in transportation.

Further objects and advantages of my invention will be more clearly understood from the following description and from the accompanying drawings in which:

Fig. 1 is a front elevational view of a frame embodying my invention, showing a picture or photograph mounted therein in dotted lines.

Fig. 2 is a side view, in central vertical section, on line 2—2 of Fig. 1.

Fig. 3 is an elevational plan view of said frame.

Fig. 4 is a side view of the bottom portion of the frame, in central vertical section, showing a modified form of the invention.

As shown in the drawings, a frame comprising my invention is preferably constructed of stiff sheet material, such as card board, fiber board, or the like, and may consist of left and right vertical members 5 and 6, which are joined together by upper and lower crosswise connecting members 7 and 8.

Each of the members 5 and 6 consist of a single sheet of material that is scored, as at 9—9, so that it may be bent, as shown in Fig. 3, to provide a front portion 10 and rearwardly extending flaps 11. The said flaps 11 pivot on the front portions 10 and have slots 12 and 13, extending diagonally thereinto from the score line to receive the rearwardly extending flaps 14 and 15 of the connecting members 7 and 8; the said connecting members having front portions 16 and 17 which are joined to the upright portions 10 at the upper corners of the frame and near the bottom portion thereof by being glued thereto or by other suitable means.

The bottom portion of each of the portions 10 of the upright members 5 and 6 may be widened out, as at 18, to provide a better appearance and also form a base for retaining the frame in an upright position upon a surface; the flap 11 being extended rearwardly to retain the frame in upright position.

It will be readily understood, from the above description, that the said frame may be easily

2

folded into a flat position by opening the flaps 11, to remove the flaps 14 and 15, of the members 16 and 17, from the slots 12 and 13, and then flattening all of said flaps one upon the other.

5 When the frame is to be set up for use, the flaps 11 are merely opened out, the flaps 14 and 15 are then inserted in the slots 12 and 13, and the picture or photograph indicated in dotted lines at 19, is placed between the said flaps 11 and against the flaps 14 and 15, as clearly shown in Fig. 3, in which position the photograph or picture will be securely retained in the frame by the inherent tendency of the portions 11 to be biased towards each other under the natural tension in the material.

When the frame herein described is set up, as shown in Fig. 1, it will provide a recessed border around the photograph or picture, in which the picture is located at the bottom of the recess and surrounded by an inclined bordering surface giving the frame as a whole a very pleasing appearance.

In the modified form shown in Fig. 4, the flaps 17 of the connecting members may be extended across the front of the upright members so as to eliminate the necessity of having the slots 12 and 13 extended as shown at 13^a and 14^a in Fig. 2 to receive these flaps.

I claim:

30 1. A picture frame of the character described constructed of sheet material and comprising a pair of left and right upright members, each of said members having a front portion with a flap hingedly connected thereto and converging rearwardly therefrom; said flaps having slots therein at an angle to the upright portion and converging towards the center of the frame, a pair of horizontal members having front portions interconnected with the front portions of the said upright members, and rearwardly extending flaps on said horizontal members fitting within said slots and terminating in free edges therein to provide an abutment against which a sheet member is retained within said frame by the rearwardly extending flaps of the upright members, and whereby the said flaps of the upright members are held in open position by abutment with the edges of said sheet member.

50 2. A picture frame of the character described constructed of resilient sheet material and comprising a pair of spaced separate upright members, each of said members being scored longitudinally to provide a front portion and a rearwardly extending flap pivoting on said front portion, an upper and a lower horizontal con-

necting member each having a front portion secured to the front portions of the separate upright members and a flap terminating in a free edge insertable within slots carried by the said rearwardly extending flaps; the said flaps of the upright members extending diagonally to the said front portion and converging rearwardly towards the center of the frame and being urged to pivot towards the free edges of the flaps on the said connecting members by the resiliency of the sheet material to secure a sheet member in said frame between the said flaps of the upright members and the free edges of the flaps of the connecting members.

3. A picture frame constructed of sheet material and comprising a left and right upright member each having a flap projecting rearwardly therefrom with a vertical slot extending inwardly from the upper and lower edge of each of said flaps adjacent the said members; the said slots extending diagonally through said flaps towards the center of the frame, upper and lower horizontal connecting members each having a front portion receivable in said vertical slots for securing it to the upright members, and a flap terminating in a free edge and extending rearwardly from each of said connect-

5
10
15

ing members into said diagonal slots for retaining the frame in opened position; the ends of said slots in the upright members being urged against the said free edges of the flaps due to the resiliency of the sheet material to thereby secure a sheet member against said free edges and between the flaps on the said upright members.
